UNITED STATES PATENT OFFICE.

HENRY E. TRUMBLE, OF KALAMAZOO, MICHIGAN, ASSIGNOR OF ONE-HALF
TO VAN H. HIGGINS, OF CHICAGO, ILLINOIS.

STEAM-ENGINE.

SPECIFICATION forming part of Letters Patent No. 424,439, dated March 25, 1890.

Application filed September 2, 1889. Serial No. 322,669. (No model.)

To all whom it may concern:

Be it known that I, HENRY E. TRUMBLE, a citizen of the United States, residing at Kalamazoo, county of Kalamazoo, State of Michigan, have invented a new and useful Steam-Engine, of which the following is a specification.

This invention relates to that class of engines which employ automatically-oscillating 10 pistons which are attached to a rock-shaft and radiate therefrom in the steam-chest.

The object of this invention consists in the construction of an engine in which the piston is composed of two plates end to end and 15 jointedly attached together and radiating from the rock-shaft, which shaft has bearings in the base of the piston-chamber, said chamber taking steam at the upper or lower end or at some point between said ends and against 20 the side of said piston.

Another object consists in a construction whereby both ends of the jointed piston have rock-bearings in the piston-chamber.

In the drawings forming a part of this specification, Figure 1 is an elevation looking from a point at the left of Fig. 2. Fig. 2 is an elevation looking from a point at the right of Fig. 1; Fig. 3, same as Fig. 2 with steam-chest removed. Fig. 4 is the same as Fig. 3 25 with one wall of the piston-chamber and the steam-chest removed and a part in section on line 3 in Fig. 5, and Fig. 5 is a section on line 2 2 in Fig. 4.

Referring to the lettered parts of the drawings, A is the piston-chamber; D, the rock-shaft, having bearings in the lower end of said chamber; and d e are two plates end to end and jointedly attached together and constituting the piston and radiating from the 30 rock-shaft. In this construction both ends of the piston have rock-bearings, one of said bearings being the bearing of the rock-shaft D, and said bearing at the other end of the piston consists of the short shaft S, which is 35 round in cross-section and which has bearings in the upper end of the piston-chamber A, Figs. 4 and 5. Said shaft S is provided with a slot in which the end of the piston plays when said piston lengthens and shortens 40 during its oscillating movements, and

during which action the shaft S oscillates in its bearings.

Referring to Fig. 3, o i are steam-ports through one of the walls C of the piston-chamber A. The position of said ports in relation to the piston-chamber is indicated by the same ports o i in Fig. 4.

In Figs. 1 and 2 a steam-chest B of the ordinary construction is shown attached to the piston - chamber so as to register with the steam-ports o i. (Shown in Fig. 3.) The steam alternately enters and exhausts through said ports o i during the oscillation of the piston from one side of the piston-chamber to the other. The steam-chest B may be attached to the piston-chamber at the particular location indicated in Figs. 1, 2, and 3, or it may be located at any other point, so as to admit steam in the piston-chamber against any portion of the sides of the piston d e.

At n is shown the steam-supply pipe, and at v is shown the exhaust-pipe in Figs. 1 and 2, and which will be readily understood without further description here.

In Fig. 1, F is a crank on the rock-shaft D, 75 to which crank a connecting-rod may be attached (said rod not here shown) for transmitting motion to other machinery. At E is the bearing to one end of the rock-shaft D.

In Fig. 2, r is the valve-rod of the valve in 80 the steam-chest, said valve not being here shown, but is of the ordinary construction and will be readily understood.

Having thus described my invention, what I claim as new, and desire to secure by Letters 85 Patent of the United States, is—

In an engine or motor, the combination of the piston-chamber and the two-part jointed piston, the ends of said piston from its central joint having rock-bearings in the two opposite ends of the piston-chamber, substantially as set forth.

In testimony of the foregoing I have hereunto subscribed my name in presence of two witnesses.

HENRY E. TRUMBLE.
